ELECTRODE ADAPTER CAP

Jerome Rosenberg, Brooklyn, N. Y.

Application March 29, 1951, Serial No. 218,137

5 Claims. (Cl. 316—2)

1

This invention relates to an apparatus for restoring damaged electrodes. More specifically, it relates to a cap for restoring contact to electrodes with broken off electrode lead wires protruding from glass neon illuminating tubes.

Neon tubes, normally used as advertising signs comprise a glass unit with a pair of electrodes with lead wires protruding from either end. These wires are inserted into an electrode housing wherein they contact high voltage cables. It is a common occurrence to find the lead-in wires broken off either because of corrosion or long usage, or burned off due to an electrical short resulting from poor contact and insulation. At this point one of two prevailing practices is used. The tube unit is removed and returned to a glassblower who must replace the electrodes, re-evacuate the tube and refill with gas. The alternate procedure is for the repairman to cut off and break away a portion of the glass end of the tube thus exposing a short length, at most $\frac{1}{8}$ ", of wire. A new wire is then laboriously bent and entwined in contact with the newly exposed electrode lead wires. The result is an inefficient, unworkmanlike job, breaking loose with slight handling, and necessitating an eventual replacement by a glassblower.

It is then an object of this invention to discover ways of and means for repairing broken-off neon tube electrode lead-wires by an on-the-spot method, eliminating return of the tube to the repair shop.

In summary, this invention comprises a cap or hood adapted to fit huggingly over the end of the electrode of the neon tube. In the top of the hood, is a conducting mass adapted to conduct power from incoming lead wires through the hood to the broken-off wires on the electrode of the tube. A more specific feature of the invention is that the contact mass is resilient and somewhat springy. Another feature is the provision of tabs or tongues on the exterior of the hood, to which incoming lead wires can be readily attached. Still another feature is the provision on the hood of friction-inducing means tending to hold the hood on the neon tube snugly and with assurance. And yet another feature is an arrangement of the conducting mass that prevents or at least minimizes danger of arcing between or across the lead wires.

The best embodiment of the invention now known to me is shown in the accompanying drawings, but it is to be understood that this embodiment is shown in an illustrative and not a limiting sense, because obviously changes and substitution of parts can be made without de-

2

parting from the ambit of the invention as defined in the appended claims.

In the drawings, Figure 1 is an isometric view of the hood of this invention, with parts broken away. Fig. 2 is a cross-sectional view taken along the lines 2—2 in Fig. 1. Fig. 3 is a partial sectional view through an end of the electrode of a neon tube, with the hood of this invention in place thereon. Fig. 4 shows a modification.

10 In the drawings, the hood or cap 11, has a top 12, and an open-ended cylindrical body portion 13. On the top 12 are tabs or tongues 14 and 15 punched from the material of the hood and bent to project somewhat from the top of the hood. 15 Bent around these tabs are the incoming power wires 16 and 16'. In the hood and closely contacting the interior of the top 12, is a contact mass 17 comprising metallic wool such as steel or copper wool but preferably bronze wool or other good conducting resilient material that can be made into a compressed but somewhat springy wad. In the cylindrical body portion 13 of the hood is slit to provide friction means comprising inwardly bent bows or fingers 18 that are depressed from the springy material of the hood. 20 In Fig. 3 the glass tube of the electrode 20 terminates in a curved closure top 21 through which extend the lead-wires 22 and 22' connected with the standard metal shell 24 of such electrodes. 25 When the lead-in wires to a neon tube become broken off, as they sometimes do right at the top 21 of the tube as shown in Fig. 3, the hood of this invention is merely slipped over the end of the tube. As the hood is pressed firmly down over the 30 end, the wad or contact mass 17 is compressed between the exposed ends of the broken-off wires 22 and 22' and makes contact between these wires and the new lead-in wires 16 and 16' that are fastened to the tabs or tongues 14 and 15 on the outside top of the hood. The hood is held in place huggingly on the tube by means of the friction-inducing springy bows 18 extending inwardly from the body portion 13 of the hood.

35 In Fig. 3 the hood is shown as being made of 40 conducting material, but it may be possible that it is preferred to make the hood of non-conducting material so that one will not get an electrical shock upon touching it. Such a modified arrangement is shown in Fig. 4, wherein the non- 45 conducting hood 113 with its top 112 has an opening 114 through which extends tabs or tongues 116 and 116' projecting from a metallic plate 115. Except for the non-conducting hood, 50 the operation of this modified embodiment is the same as that of Fig. 3.

55 With the wad of metallic wool 17 in place, a

3

positive electrical contact is made. Thus the need for cutting down or mutilating the electrode is eliminated, particularly for the unskilled repairman who is uncertain about his ability to make a cut as previously described. The top portion 21 of the electrode thus cushioned into the enclosed conducting wool 17 furnishes an effective contact with the electrode lead wires. Though these lead wires 22 and 22' may be unexposed, the top surfaces of the glass encased wires are available to contact. The snugness and proximity of the wool to the exposed lead wire surfaces eliminates the possibility of striking an arc between the two points because the neon unit when installed and in the housing is always pressed into the housing against the opposite pressure of the springs within the housing. Consequently, the hood, when in place, is always forced on tighter, never the reverse, enhancing the improbability of striking an arc between the electrode wires and the wool.

With this hood, the present practice of repairing with an insecure twisted wire joint is eliminated. Perfect contact is made not only to the power supply through the new cap lead wires, but also to the old electrode lead-wire stubs through the metallic contact mass of the hood. The neon serviceman may use this hood at the point where the broken tube is located eliminating needless trips back to a repair shop. Glass-blowers' costs are minimized by this hood and the user of the neon tube benefits because he has his unit back in operation sooner than he would if it had to be removed and returned to a repair shop.

As can be seen from Fig. 4, it is also within the ambit of this invention to include a unit in which the conducting upper plate, to which the new electrode lead wires are attached, is formed as a separate piece, distinct from the hood. The hood is fabricated from a non-conducting material, such as certain plastics. The hood has an opening in the upper portion through which are led the new electrode lead wires, attached to the conducting separate upper plate. Thus the 45

4

hood does not carry any electricity, and if accidentally touched by one cleaning or otherwise working around the end of the repaired tube, there would be no electrical shock. The only portions of the repaired unit which carries electricity, are the new two lead-wires which project through the hole in the plastic hood. The metallic plate is totally enclosed by the plastic hood.

10 This is a continuation-in-part of my parent patent application Serial No. 157,227, filed April 21, 1950 now abandoned.

I claim:

15 1. A neon tube repair hood, comprising a hood adapted to enclose a neon tube electrode and having a closure top, a lead wire affixed to the top, and a contact mass of electrically conducting wool engageable with the electrode inside the hood while in contact with the top on its inner surface.

2. A hood according to claim 1, wherein the hood has an upper plate that alone is electrically conducting, and a lead wire affixed to the plate on its outer surface.

25 3. A repair hood according to claim 1, wherein the side of the hood has inwardly projecting friction means for frictionally engaging the electrode.

4. Apparatus for repairing neon tube electrodes, comprising a circular non-conducting hood with unitary sides and a top with an opening therein, a separate conducting plate adapted to fit within said hood, and lead wires attached to one surface of the conducting plate and adapted to pass through the opening in the top.

35 5. The process of repairing a damaged neon tube electrode comprising contacting neon electrode lead wires with a wad of electrically conducting wool, and contacting the wool with the surface of a conducting plate to which is attached a lead wire on its opposite surface.
